UNITED STATES PATENT OFFICE.

JAMES T. HOGAN, OF JERSEY CITY, NEW JERSEY, ASSIGNOR TO THE NATIONAL MACHINE COMPANY, OF NEW YORK, N. Y., A CORPORATION OF NEW YORK.

BUTTONHOLE-SEWING MACHINE.

SPECIFICATION forming part of Letters Patent No. 694,151, dated February 25, 1902.

Application filed February 26, 1901. Serial No. 48,948. (No model.)

To all whom it may concern:

Be it known that I, JAMES T. HOGAN, a citizen of the United States, residing in Jersey City, county of Hudson, and State of New Jersey, have invented a new and useful Improvement in Buttonhole-Sewing Machines, of which the following is a specification.

My invention relates to a buttonhole-sewing machine, and has for its object to produce 10 an automatic mechanism by which a buttonhole may be sewed having rows of side stitches and barring-strokes, the latter at substantially a right angle to the former, across the end of the buttonhole.

15 I will describe a buttonhole-machine embodying my improvement and then point out the novel features in claims.

In the accompanying drawings, forming part of my specification, and in which similar 20 letters of reference indicate similar parts, Figure 1 is a side elevation of a machine embodying my improvement, a portion of the base being broken away. Fig. 2 is a plan or top view of certain parts and a horizontal section of others. Fig. 3 is an inverted plan view of the parts on the underside of the bed-plate of the machine. Fig. 4 is a sectional view on the plane of the line 4 4, Fig. 3. Fig. 25 5 is a sectional view on the plane of the line 5 5, Fig. 3. Figs. 6 and 7 are diagrammatic views illustrating the position of side and barring strokes in a buttonhole, (they are not, however, intended to indicate the character of the strokes,) and Fig. 8 is a face view of a 30 modified form of cam that may be used to sew a buttonhole of the character shown in Fig. 7, and Fig. 9 is a detail view of two pawls employed by me.

A designates a sewing-machine head of any 35 suitable form. As shown, it has a bed-plate A' and a horizontal arm A². The needle-bar A³ is fitted in the usual frame in the front of the machine and is reciprocated vertically in the usual manner by a crank and pitman, actuated by a main driving-shaft A⁴.

40 The machine will be provided with a suitable form of well-known cutter mechanism to cut the buttonhole either before or after sewing. The machine will also be provided 45 with any suitable form of work clamp or sup-

port, that shown in the present drawing forming the subject-matter of a patent granted to me September 11, 1900, No. 657,540.

A⁶ designates a shuttle mechanism actuated in the usual manner by the pitman A⁷. 55

My invention comprises means to produce a relative feeding movement between the sewing mechanism and the work-support lengthwise of a buttonhole and simultaneously therewith a relative vibratory movement between said devices to sew a row of side stitches. After the completion of a row of side stitches these relative movements are suspended, and after such suspension relative feeding and oscillating movements are produced between 60 the sewing mechanism and the work-support to produce a set of barring-strokes at substantially right angles to the side stitches. The relative movements necessary in the sewing of the barring-strokes are then suspended, and the relative movements necessary for the sewing of the second row of side stitches are produced. Finally the relative movements necessary for the sewing of the second row of barring-strokes are produced. In the 65 present example of my improvement I have shown means whereby the needle is vibrated and the work-support fed lengthwise of a buttonhole during the sewing of a set of side stitches, and whereby the needle is reciprocated only and the work-support moved transversely, and at the same time oscillated longitudinally of a buttonhole during the sewing of barring-strokes. I will describe first the 70 mechanism for sewing a row of side stitches. 75

D designates a vertical shaft driven in the usual manner by gears from the main driving-shaft. On a disk D⁸, secured to shaft D, is an ordinary triangular cam D⁴. D⁵ designates a lever fulcrumed on a stud d. This 80 lever is oscillated on its fulcrum by means of the cam D⁴, working in a slot in said lever. Connected to the slotted end d' of the lever D⁵ is a pitman E, the forward end of which is connected to a pawl-carrier plate E'. On 85 this pawl-carrier plate are mounted two spring-pressed pawls e' and e², lying side by side, the toe of the pawl e' being twice the width of the toe of the pawl e², for the purpose hereafter described. The pawl e' en- 90

gages the ratchet-wheel E^2 , rotatively mounted on a stud in the bed of the machine. Lying below the wheel E^2 is a toothed sector-plate e , the purpose of which is to suspend 5 the lengthwise-feeding movement of the work-support at the end of the sewing of the side stitches. This plate e is engaged at the proper time by the narrow pawl e^2 . Projecting downwardly from the ratchet-wheel E^2 through 10 an opening in the plate e is a pin e^3 . This pin projects between the bifurcated arm e^4 , secured by suitable means to a pinion E^4 . This pinion is mounted on a bracket E^5 eccentrically of the ratchet-wheel E^2 and the 15 toothed sector e . The pinion E^4 meshes with a gear-wheel E^3 , which wheel is fixed to a stem e^5 by any suitable means, preferably screws. The stem e^5 extends upwardly 20 through a boss e^6 and has secured to its upward end a plain disk E^6 . The disk E^6 is provided with a diametrical slot which receives the head of a screw-bolt, and over this bolt the end of a pitman E^7 is passed, being clamped into position by a cap engaging the 25 screw-thread of the bolt. Said cap has a handle e^7 to manually operate the disk E^6 . The other end of the pitman E^7 is secured to a slide-block E^8 , fitting in a groove q^2 of the main plate Q . The slide-block E^8 is secured 30 to the work-support in any suitable way.

It will be readily seen from the above description that the step-by-step rotary movement of the ratchet-wheel E^2 will impart to the work-support a progressive movement 35 lengthwise of a buttonhole during the sewing of side stitches. During this lengthwise-feeding movement of the work-support the needle is given a vibratory movement at right angles to the lengthwise movement of the 40 work-support by the following mechanism, which is fully described in an application filed by me June 30, 1899, Serial No. 722,397. This mechanism comprises a bevel-gear (not shown) in the head of the machine and actuated by the main driving-shaft A^4 . The 45 driven gear-wheel has made integral therewith or separate and attached thereto by suitable means a disk cam. Engaging the cam-groove is a follower b , secured to a lever B , which lever is fulcrumed on a stud or shaft b' , extending through the arm A^2 . A link B' is connected to the free end of the lever B and to a bracket or extension B^3 of a rock-lever B^3 . The lever B^3 is fulcrumed at its 50 center on a stud b^4 , which stud has a bearing on a plate (not shown) fastened to the plate B^4 . The lever B^3 is made with side pieces, as shown; so as to form a longitudinal groove b^3 , and slidably supported in this groove is a 55 block B^5 , provided with a boss or projection, on which are mounted the end of a pitman C and an end of an upright rod C' . The forward end of the pitman C is connected to the needle-bar frame. The rocking of the 60 lever B^3 through the lever B and link B' will impart a vibratory movement to the needle-bar when the block B^5 is above or below the

fulcrum of the lever B^3 . To determine the position of the block B^5 with reference to the fulcrum of the rock-lever B^3 , I have provided 70 the following mechanism.

F designates a three-step cam secured to the under face of the gear-wheel E^3 . This cam has the faces f , f' , f^2 , and f^3 , the face f being the highest, the face f' being the lowest, and the faces f^2 and f^3 being in the same 75 horizontal plane and half-way between the planes of the faces f and f' . Between the face f^3 and the adjoining faces of the cam are inclines. (Shown by shading.) Between the face f^2 and the adjoining faces are vertical walls. (Shown by the two straight lines.) Actuated by the cam F is a lever F' , fulcrumed on a bracket F^2 , attached to the base-plate. The lever F' is provided with a follower or 80 toe-piece F^3 . The free end of the lever F' is secured to a stud on the end of the vertical rod C' , which rod is surrounded by a spring C^2 , held between the bed-plate of the machine and a collar c on said rod, the function of said 85 spring being to hold the follower F^3 into close contact with the different faces of the cam F .

The operation of the mechanism just described is as follows: During the sewing of the first row of side stitches the cam F is so 95 adjusted that the face f supports the lever F' and the rod C' , so as to hold the block B^5 above the fulcrum of the lever B^3 . This position of the block B^5 is maintained until the follower F^3 reaches the incline between the faces f and f^3 . The continued rotation of the gear-wheel E^3 carries the follower F^3 from the face f to the face f^3 . This movement of the follower lowers the rod C' , so as to bring the block B^5 coincident with the fulcrum of the rock-lever B^3 , when the vibratory movement of the needle-bar will be suspended. As before described, the rotation of the gear-wheel E^3 is effected through the medium of the ratchet-wheel E^2 . When it becomes necessary to suspend the vibratory movement of the needle-bar, as just described, it is necessary at the same time to suspend the lengthwise-feeding movement of the work-support. This is effected by means of the toothed sector e , the 105 periphery of which extends beyond the teeth of the wheel E^2 . The pawl e^2 is in advance of the pawl e' , so that when the ratchet-wheel E^2 has been fed by the pawl e' to complete the sewing of a row of side stitches the said 110 last-mentioned pawl is thrown out of engagement with said ratchet-wheel and passes into engagement with the teeth of the sector e , thereby suspending the lengthwise-feed movement of the work-support. The advantage 115 in employing two pawls is that the feed may be adjusted too fine to permit of the pawl e' riding over the shoulder of the sector e . By placing the pawl e^2 in advance of the pawl e' the former will engage the teeth of said sector, so as to give it a positive movement and bring it into position to be engaged by the pawl e' . The parts which thus give a vibratory movement to the needle and a length-

wise feed to the work-support remain suspended at the end of the sewing of the side stitches and during the time that barring-stitches are being formed. The length of this suspension is determined by the number of teeth in the sector *e* and by the extent of throw of the pitman *E*, which latter is determined by the position of the end of said pitman in the slot *d* of the lever *D*. When the pawl *e* reaches the end of its travel on the sector *e*, said pawl and also the pawl *e* falls into engagement with the teeth of the wheel *E*, thus beginning again the rotation of said wheel and the feeding of the work-support to sew the second row of side stitches. The rotation of the gear-wheel *E* carries the follower *F* from the face *f* to the face *f'* of the cam *F*, causing thereby the rod *C'* to move downward, carrying the block *B* below the fulcrum of the rock-lever *B*. This position of the end of the pitman *C* vibrates the needle, so as to sew edge and depth stitches along the other side of the buttonhole. These movements of the work-support and needle continue until the end of the buttonhole is reached, when the second set of barring-stitches will be sewed, at which time the follower *F* will drop from the face *f'* to the face *f*, the spring *C* then raising the rod *C'* to bring the block *B* coincident with the fulcrum of the rock-lever *B*, thereby suspending the vibratory movement of the needle. The ratchet-wheel *E* makes two complete rotations for the sewing of each buttonhole, so that when the second bar is to be sewed the sector *e* is brought into position and operates as heretofore described in sewing the first bar.

Having described the means for sewing the side rows of stitches and for suspending the vibratory movement of the needle and the lengthwise-feeding movement of the work-support during the sewing of the barring-stitches, I will now describe the means for sewing the barring-stitches.

G designates a pitman connecting the lever *D* at its slotted end *d* and the pawl-carrier lever *G'*. Extending through the pawl-carrier lever is a shaft *I*, surrounded by the boss *g* of a feed-wheel *G*, the pawl-carrier lever being mounted so as to oscillate on said boss. *g* and *g'* are two spring-pressed pawls mounted on the lever *G'*, engaging the feed-wheel *G*.

Fulcrumed on a stud secured to the bed-plate of the machine is a bell-crank lever *H*, the arm *h* of which is curved at its outer end, as shown. A spring *H'*, secured to the arm *h* and to the bed-plate of the machine, causes the arm *h* to hold the pawl *g'* out of contact with the feed-wheel *G* during the sewing of the side stitches, so as to render the said pawl inactive. During this time—that is, during the sewing of the side stitches—the pawl *g* is also rendered inactive by means of the blind tooth *g*, the said pawl merely riding over said tooth during the oscillation of the lever *G'*. To bring the feed-wheel *G* into action when barring-stitches are to be sewed, I provide a

cam-piece *h* on the toothed sector *e*, which trips the arm *h* of the bell-crank lever *H* at or about the time the follower *F* is brought onto either one of the faces *f* or *f'* of the cam *F*. During the sewing of the side stitches the pin *g* merely rides over the curved face of the arm *h*. When, however, the arm *h* is tripped by the cam *h*, the arm *h* is thrown outward into such position that the spring *g* will throw the pawl *g'* into engagement with the teeth of the feed-wheel *G*. As soon as this occurs the said wheel will be fed a sufficient number of teeth to carry the blind tooth *g* beyond the pawl *g*, so as to enable the pawl *g* to continue the rotation of the wheel *G*. The barring begins as soon as the pawl *g'* begins to feed, and the cam *h* is of sufficient length to cause the pawl *g* to feed the wheel *G* far enough to bring the pawl *g* into action. This may be for one, two, or more teeth of the wheel *G*, and when the end of the arm *h* passes out of contact with the cam *h* the arm *h* assumes such position through the spring *H'* as to throw the pawl *g'* out of engagement with the feed-wheel *G*. The rotation of the wheel *G* continues through the action of the pawl *g* until the said pawl is brought opposite the blind tooth *g*, when the rotation of said wheel ceases. When this occurs, the barring will have been completed and the parts brought to position for the sewing of the second row of side stitches.

The work-support during the sewing of the barring-stitches is moved in a straight line, and at the same time oscillated through cams actuated by the feed-wheel *G* by the following means: The shaft *I* passes through a bushing in the bed of the machine. On top of said shaft is a flange (not shown) forming a support for two cams *N* and *O*. These cams may be cut on the two sides of one plate or they may be made separate and fastened together by suitable means. The groove of the cam *N* is cut so as to impart an oscillating movement to the work-support, and the cam *O* is of such shape as to impart to the work-support a feeding movement in a straight line. Such cam is usually referred to as a "heart-cam" and will be readily understood by such designation.

L designates a plate resting on the bed of the machine and moving between gibbs *l* and *l'*, said plate being cut away to provide a clearance for the bearing of the shaft *I*. Plate *L* is provided with a follower *l*, which follower engages the groove of the under cam *N*. The plate *L* is slotted, as shown at *l*. In this slot travels a follower on a stud *l*, which stud extends upwardly through a slot *p* in the arm *p* of a plate *P*, the said stud being clamped to said arm *p*. The plate *P* is secured by means of screws to the main plate *Q*. The plate *Q* is cut away at *q*, and in this recess is a guiding-block *Q'*, bearing against the inner side walls of said recess. The block *Q'* is loosely mounted on a round stud, which receives a cap-screw *q*. The plate *P* is thus

pivoted on the block Q', and the reciprocating movement of the plate L imparts an oscillatory movement to the main plate Q and to the work-support secured to said main plate Q' in a direction lengthwise of the buttonhole. At the same time that the work-support is moved as just described it is also given a movement in a straight line in a direction at right angles to the buttonhole through the cam O. This is effected by the follower r on the end of an arm R, secured by screws, as shown, to the plate P, it being clear that the movement in a straight line of the plate P will be imparted through the main plate Q to the work-support.

In Fig. 6 I have shown diagrammatically a buttonhole as sewed on the machine organized as described. Starting at the end x a row of side stitches is sewed on the left-hand side of the buttonhole, the goods being fed toward the operator. At the end of the sewing of this first row of side stitches the needle is on the center line of the buttonhole at the point y. The movements for producing the vibratory movement of the needle and the lengthwise-feeding movement of the work-support are suspended at or about this time, and the sewing of the barring-stitches begins. The cams N and O are so constructed and timed as to sew a set of barring-stitches beginning from the center line of the buttonhole to the right and extending to about the end of the depth-stitches on the side, then to the left across the end of the buttonhole to the end of the depth-stitches on the other side of the buttonhole, and finally back to the center of the buttonhole-line. The parts are then in position to sew the second row of side stitches when the feed is away from the operator. The barring-stitches at the end x are formed outwardly and at substantially right angles to the side stitches—that is, with the form of the cams N and O shown in Fig. 2 the barring-stitches do not overlap the side stitches. At the end y, however, the feed of the mechanism to form the barring-stitches being in the same direction as the end x, the barring-stitches will overlap two or three of the side stitches, as shown in the drawing.

In Fig. 8 I have illustrated a modification of the cam N for the purpose of causing the barring-stitches to overlap the side stitches at both ends of the buttonhole. Instead of cutting the groove of the cam N, so as to make the throws of the work-support equal for all of the barring-stitches, I make the recess n' —that is, the recess in which the follower l^4 rests during the formation of the side stitches—half the depth of the throw of the cam from the point n^2 to the point n^3 . As so constructed the cam N on its first and last throw for a set of barring-stitches will move the work-support but half the distance of its throw for the remainder of the barring-stitches. It is evident from this that when the needle starts from the center of the buttonhole-line the work-support will be moved half the dis-

tance of a full throw. On the second and succeeding stitches the work-support will be moved the full distance of the throw of the cam N until the last barring-stitch, which will be of the same length as the first one, bringing the needle to the starting-point. This will occur at both ends of the buttonhole, as shown in Fig. 7. The tension of the needle-thread being constant during the sewing operation, a purl-stitch will be formed in both the side and barring stitches. To get the benefit of the tension, it is of advantage to cover up the first one or two of the side stitches by the barring-stitches.

It will be observed from the foregoing description that during the sewing of barring-stitches the work-support will be given an oscillatory movement about the block Q' as a pivot—that is, the work-support will be moved in the arc of a circle and not as in my previous application, Serial No. 722,298, in a straight line—so that the barring-stitches will be laid at substantially right angles to the side stitches.

Instead of making plates P Q and the shank of the work-support in separate pieces it is evident that they may be made of a single piece of metal.

What I claim, and desire to secure by Letters Patent, is—

1. In a buttonhole-sewing machine the combination with stitch-forming mechanism of a work-support, means for producing between said stitch-forming mechanism and work-support relative feeding and vibratory movement suitable for forming rows of stitches for the sides of a buttonhole, and mechanism for producing relative feeding and oscillating movements between the stitch-forming mechanism and the work-support, to form barring-stitches at substantially right angles to the side stitches, said last-named means comprising a plate and an extension of the work-support and two cams to simultaneously actuate such plate and work-support, substantially as described.

2. In a buttonhole-sewing machine the combination with stitch-forming mechanism, of a work-support, means for producing between said stitch-forming mechanism and work-support relative feeding and vibratory movements suitable for forming rows of stitches for the sides of a buttonhole and means for producing barring-stitches at both ends of and at substantially right angles to, the rows of side stitches, comprising a feed-wheel having a blind tooth, a lever carrying two pawls, one of which engages said tooth during the formation of the side stitches, a lever to hold the second of said pawls out of engagement with said wheel during the formation of side stitches, and means to trip said lever to permit the last-named pawl to move said wheel to bring the first-named pawl into active relation with the feed-wheel, substantially as described.

3. In a buttonhole-sewing machine, the com-

5 bination with stitch-forming mechanism, of a work-support, means for producing between said stitch-forming mechanism and work-support relative feeding and vibratory movements suitable for forming rows of stitches for the sides of a buttonhole, means to suspend said movements; means to produce barring-strokes, comprising a main plate, a second plate pivoted on a block supported in an 10 opening in the main plate, and means to impart to said second plate a movement in a straight line transversely to the length of the buttonhole and at the same time to oscillate it in a direction at right angles to such trans- 15 verse movement, substantially as described.

4. In a buttonhole-sewing machine the combination with stitch-forming mechanism, of a work-support, mechanism for producing between said stitch-forming mechanism and work-support relative feeding and vibratory movements suitable for forming rows of stitches for the sides of a buttonhole, means to suspend said movements at a predetermined period, and means to form barring- 20 stitches, consisting of a plate connected to the work-support, means to feed said plate in a straight line transversely to the length of the buttonhole and at the same time to oscillate it in a direction at right angles to such 25 transverse movement, substantially as described.

30 5. In a buttonhole-sewing machine the combination with stitch-forming mechanism, of a

work-support, means for producing between said stitch-forming mechanism and work-support relative feeding and vibratory movements suitable for forming rows of stitches for the sides of a buttonhole, and mechanism for feeding and oscillating the work-support relatively to the needle to form barring- 35 stitches at both ends of and at substantially right angles to the aforesaid rows of side stitches, said mechanism including an extension of the work-support, substantially as described. 40 45

6. In a buttonhole-sewing machine, the combination with stitch-forming mechanism comprising a needle and a work-support, mechanism for producing between said stitch-forming mechanism and work-support a relative 50 feeding and vibratory movement suitable for forming rows of stitches for the sides of a buttonhole, and mechanism for producing a relative feeding and oscillating movement for forming barring-strokes at the ends of the 55 buttonhole, at substantially right angles to the side stitches, said mechanism including an extension of the work-support, substantially as described.

In testimony whereof I have signed my 60 name to this specification in the presence of two subscribing witnesses.

JAMES T. HOGAN.
